UNITED STATES PATENT OFFICE.

FELIX VALLIÈRE, OF GROVETON, NEW HAMPSHIRE.

HARNESS-HAME.

1,116,175.

Specification of Letters Patent.

Patented Nov. 3, 1914.

Application filed November 19, 1909. Serial No. 528,927.

To all whom it may concern:

Be it known that I, FELIX VALLIÈRE, a citizen of the Province of Quebec, Canada, residing at Groveton, in the county of Coos 5 and State of New Hampshire, have invented new and useful Improvements in Harness-Hames, of which the following is a specification.

This invention relates to harness hames, 10 and it has for its object to provide a simple and improved attachment for the same which may be applied without seriously mutilating or weakening the hames for the purpose of constituting a trace-attaching 15 device.

A further object of the invention is to provide a simple and improved device which may be clamped and firmly held upon the hames without mutilating the latter; said 20 attachment being held in position against sliding by means of one or more light bolts extended therethrough.

Still further objects of the invention are to simplify and improve the general construction and operation of a device of the 25 character outlined above.

With these and other ends in view which will readily appear as the nature of the invention is better understood, the same 30 consists in the improved construction and novel arrangement and combination of parts which will be hereinafter fully described and particularly pointed out in the claim.

In the accompanying drawing has been 35 illustrated a simple and preferred form of the invention, it being, however, understood that no limitation is necessarily made to the precise structural details therein exhibited, but that changes, alterations and modifications 40 within the scope of the invention may be resorted to when desired.

In the drawing,—Figure 1 is a front view of a hame equipped with the improved attachment. Fig. 2 is a rear view of the same. 45 Fig. 3 is a transverse sectional view on a larger scale taken on the plane indicated by the line 3—3 in Fig. 1. Fig. 4 is a perspective detail view also enlarged of the improved device.

50 Corresponding parts in the several figures are denoted by like characters of reference.

The improved device, which constitutes the subject matter of this invention, consists of a plate 5 of suitable dimensions and of 55 approximately semi-circular cross section, said plate being suitably shaped to be fitted

against and to abut tightly upon the curved front side of an ordinary hame A. The plate 5 is provided adjacent to one of its edges with laterally extending thickened 60 reinforcing lugs 6 and 7 which are formed integral therewith, said lugs being of substantially rectangular configuration and provided with aligned apertures 8 for the passage of a trace-attaching bolt 9; the lower 65 lug 7 is additionally provided with a downward extension 10 having a longitudinal aperture 11 in which a harness ring 12 may be mounted. The downward extension 10 terminates below the lowermost longitudinal 70 edge of the plate 5 whereby the harness ring 12 will have free swinging movement and will not be obstructed from having such movement by the plate 5.

The plate 5, which in practice is preferably formed by the casting of malleable iron, or other suitable malleable metal is provided along one of the transverse edges thereof with a series of outwardly extending teeth or lugs 15, while its opposite transverse edge is provided with a pair of outwardly extending sharp pointed teeth 15' and owing to the nature of the material of which the device is constructed, may be readily bent by striking said teeth or lugs 80 with an ordinary hammer. The lugs 6 and 7 are formed at a point adjacent to the respective teeth 15' and tending to reinforce the side of the plate which is liable to undue stress, or in other words reinforcing 85 the plate at a point adjacent to the tracing bolt 9. The plate is also provided intermediate its edges with one or more apertures 16 for the passage of fastening members, such as bolts 17, whereby the plate may be 90 secured upon the hame against longitudinal displacement.

In the operation of this device, the plates 5 are mounted upon hames and are firmly secured upon the latter by means of the 100 teeth or lugs 15 which are bent or upset upon the rear sides of said ends in which they may, if desired, be lightly embedded, as will be best seen in Fig. 3 of the drawings. While the plates are in this manner secured upon the hames for all practical purposes, it is deemed advisable to add the fastening bolts 17 for the purpose of absolutely preventing longitudinal displacement of said plates. 105

110 From the foregoing description taken in connection with the accompanying drawing,

the operation and advantages of this invention will be readily understood. The improved device or attachment is extremely simple and inexpensive, and it is capable of being applied to hames without injuriously mutilating the latter so as to seriously detract from their strength and wear-resisting qualities. The device forming the improved attachment has been found thoroughly efficient for the purposes for which it is provided.

Having thus described the invention, what is claimed as new, is:—

As an article of manufacture, a hame attachment consisting of a malleable plate of substantially semi-circular cross section and having one of its transverse edges formed with a series of sharp pointed teeth and its other transverse edge formed with a pair of spaced sharp pointed teeth, the latter mentioned teeth being formed at a point flush with the respective upper and lower longitudinal edges of said plate, said plate

being provided on its outer face at a point adjacent each of the last mentioned teeth with angularly arranged thickened apertured lugs, said lugs being of substantially rectangular configuration and disposed in superposed relation one to the other and adapted to reinforce one of the transverse edges of the plate, one of said lugs being threaded for the reception of a bolt, said threaded lug being also provided with a downward extension having an aperture substantially at right angles to the vertical aperture for the reception of a harness ring, said extension terminating below the lowermost plane of the longitudinal edge of the plate whereby the harness ring is unobstructed for free swinging movement.

In testimony whereof I affix my signature in presence of two witnesses.

FELIX VALLIÈRE.
